United States Patent

Des. 239,823
Patented May 11, 1976

239,823

TRUCK CAB BODY

Jean Juillet, Lyon, Rhone, France, assignor to
Automobiles M. Berliet, Lyon, France

Filed Sept. 12, 1974, Ser. No. 505,579

Claims priority, application France Mar. 14, 1974

Term of patent 7 years

Int. Cl. D12—08

U.S. Cl. D12—96

Fig. 1

Fig. 2

Fig. 3

Fig. 4

FIG. 1 is a front elevational view of a truck cab body showing my new design;

FIG. 2 is a left side elevational view of FIG. 1, the right side being a mirror image thereof;

FIG. 3 is a perspective view of FIG. 1; and

FIG. 4 is a rear perspective view of FIG. 1 with the front bumper omitted for convenience of illustration.

The broken lines in the drawing are for illustrative purposes only.

I claim:

The ornamental design for a cab body, as shown and described.
